UNITED STATES PATENT OFFICE.

ELMER A. SPERRY, OF CHICAGO, ILLINOIS.

GAS-ENGINE.

SPECIFICATION forming part of Letters Patent No. 433,551, dated August 5, 1890.

Application filed December 12, 1887. Serial No. 257,716. (No model.)

To all whom it may concern:

Be it known that I, ELMER A. SPERRY, a citizen of the United States, residing at Chicago, in the county of Cook and State of Illinois, have invented a certain new and useful Improvement in Gas-Engines, of which the following is a specification.

My invention relates to gas-engines, and my object is to provide a gas-engine in which many of the disadvantages adherent in the ordinary construction of gas-engines shall be obviated, as hereinafter set forth.

The invention is substantially illustrated in the accompanying drawings herein.

Figure 1 represents a diagrammatic view of an engine embodying some of the principles of the present invention. Fig. 2 represents a vertical section through the cylinders and pistons, showing the mixing, governing, and igniting devices and other features. Fig. 3 represents a detail, showing one of the piston-rods and the piston of the pump and one of the packing-glands. Fig. 4 represents a sectional view of a portion of the combustion-cylinder, showing the cored passages containing the piston-rods. Fig. 5 represents a side elevation of a complete engine for the purpose of showing the general arrangement of parts. Fig. 6 represents a section of the cylinders and pistons through the exhaust-valves, showing means for driving the same, the ignitor, showing also the check-valves leading from the pump to the combustion-cylinder, the deflector for the incoming gases, and other features.

In these figures similar letters of reference refer to like parts throughout.

The letters A A indicate two combustion-cylinders, fitted each with a plunger-piston A'. A² A² indicate two single-acting air-pumps, with pistons A³ having a driving-connection with a piston-rod a, as shown, which connects the pump-piston A³ to the connecting rod or pitman a' by means of the cross-head a² and gland or packing-box a³.

B indicates the crank of the power-shaft, and B' an auxiliary connection from the crank-pin to a bell-crank lever B² for operating the exhaust-valves b b, as will be more fully described.

A forked lever is shown at b' for operating

the ignitors C C by contact with the cross-head e² when in its extreme position.

Means are shown for holding the lever b' in a central position when not engaged in either direction by the cross-head. Double valves C' C' are shown between the air-mixture pumps A² A² and the combustion-cylinders.

C² indicates the induction-port and valve 60 for admitting the mixture to the pump.

It will be noticed that the exhaust-valves are operated by the contact of the stop B² upon the rod C³, projecting from the lever B², driven from the crank-shaft, as shown, the 65 arrangement being such that during each alternate half of the revolution of the crank-shaft each exhaust-valve b is opened and the other remains closed. Its stop P³ recedes from the exhaust-valve connection. 70

By reference to Figs. 2, 3, 4, and 5 the component elements represented in the foregoing diagrammatic view may be easily traced. In Fig. 2 the two ends of both the cylinders and pistons are similar to each other, as will be 75 seen in the drawings. An elongated cylinder A A² A is bored of the same diameter at each end A A for about one-third total length. The middle one-third is of larger bore A². A cylindrical piston A' A' is turned to fit the two 80 smaller bores at the ends of this compound cylinder, and is provided with rings b² for the purpose of packing the same. Centrally located upon this compound piston is an annular projection (indicated by A³) turned to accurately fit the larger bore A² of the compound cylinder. This projection serves as a piston for the pump or mixing cylinder. It is to this annular piston that the piston-rods a are attached. (See Figs. 3 and 4.) These 90 pistons are secured to the opposite sides, or may be in any other suitable location. The stuffing boxes or glands a³ are provided at the end of a cored passage terminating in an aperture in the cylinder-head b³, leading from 95 the mixing-cylinders, as shown. The pistons are secured to the cross-head a², guided and attached by the pitman a' in the usual manner. (See Fig. 5.) The three pistons are preferably made of a single casting provided with 100 two cored passages D D', leading from the mixture-cylinder upon either side of the pis-

ton a^3 to the combustion-cylinders. Each of these are provided with a suitable valve C' , opening into a combustion-cylinder. The preferred construction is shown in Fig. 2. This 5 valve is mounted in a separate casting, which covers the end of the cored passage, and also covers the larger internal core, by means of which the casting is lightened. This casting is provided with a lever c and a weight c' on 10 the opposite side of the fulcrum c^2 from that in contact with the valve C' . The momentum effect of this weight and lever upon the valve is opposite to that of said valve.

In Fig. 6 two check-valves, coupled in series, 15 connect the cored passages $D D'$ with the combustion-cylinders. Guides of the usual sort are provided for the moving part of these valves, so that the motion of the piston cannot prevent them from "seating" properly. 20 These valves are opened by the pressure of the mixture in the pump-cylinder a^2 . The usual water-jacket E is provided in the walls of the combustion-cylinders and cylinder-heads b^3 . A tubular extension is provided to 25 conduct the gases after they have passed the two valves $c' c'$, the office of which will be more fully explained.

In Fig. 2 the exhaust-ports h^2 are uncovered by the advancing piston in the last portion of 30 its stroke, whereas in Figs. 1 and 6 the exhaust-passages are controlled by valves b .

In Fig. 2 the arrangement of induction-valves is shown, and also the mixing-valves and devices at each end of the double-acting 35 pump-cylinder A^2 and in the passage C^2 . The induction-valve E' is provided. A stem E^2 is guided suitably below, and at its lower extremity is provided with an enlarged portion supporting the cushion E^3 , generally of raw- 40 hide. Immediately under these rawhide cushions are screws e , working in the screw-threaded caps e' . The upper ends of these screws are adapted to support the valve E' by engaging with the cushion enlargement 45 E^3 of the valve-stem before the valve is in contact with its seat. The distance which the valve is elevated off its seat and supported in that position is determined by the height to which the screw is raised by turning the same in its screw-threaded socket e' . 50 This is effected by any suitable governing device. The centrifugal governor F is shown mounted upon the crank-shaft B of the engine. The balls F' in being thrown from the 55 center by the centrifugal force move the sleeve F^2 along upon the shaft, vibrating the bell or crank lever F^3 about its fulcrum F , drawing thereby the rod f' , connected between said lever and the screw, thereby turning 60 the screw e by means of the laterally-projecting arm f^2 , secured to the lower extremity of said screw e . The link F^3 connects the two arms of the two screws and compels them to move simultaneously, thus 65 preventing the valves at both ends of the cylinder from seating themselves each to the same extent as the other. As the piston A^3

sweeps from one end to the other of the cylinder A^2 , (if the valves E' are supported above their seats,) the gases pass out partially by 70 way of these valves, which communicate with each other on their under sides by passage $G G'$, so that the mixture which escapes before the advancing piston at one end is thrown into the cylinder at the other end and no extra tension is given nor power wasted. Under the center of this last-named passage is the combination-valve G' , covering both the air-passages G^2 and the gas passages or openings G^3 , leading from a centrally-located in- 75 closed cavity g , connected to the gas-supply. This cavity is covered by the cap g' , provided at its center with an aperture for the valve- 80 stem g^2 , provided with the cap and spring g^3 . The valve G' bears a circular collar at its 85 outer periphery, which approaches very near the bore of the lower circular portion of the cavity G . Through this narrow annular passage the air and gas are compelled to pass, and are thereby mixed thoroughly. A wire- 90 gauze cap H is, however, provided to aid the mixing by cutting up the incoming mixture by means of its mesh. The valve G' lifts in 95 response to any suction of either end of the cylinder A^2 from the common passage G , sup- 95 plying thereby the amount passed out to the combustion-cylinder A' through the valve C' . This amount depends upon the closeness with 100 which the valves E' are allowed to rest upon their seats. The cylinders are cast in two parts, having a joint at H to facilitate in the manufacture.

The piston A^3 receives the four piston-rods $a a a a$. (See Figs. 3 and 4.) These are secured, as shown, and pass out through cored 105 passages and glands a^3 and attached to the cross-head a^2 . The peculiar position of these rods necessitate a certain minimum difference of diameter between the two cylinders for 110 obvious reasons. For some reasons this difference of diameter is too much and gives more area to the pump-piston than is required. The reason referred to is that the securing of the piston-rod a to the piston A^3 should be 115 so accomplished that sufficient metal is left upon the exterior of the piston to provide strength against any excessive pressure or strain which the same is called upon to withstand. I obviate this by a releasing-passage h and h' , (see Figs. 2 and 6,) by means of which 120 the two are driven a short portion of their stroke, coupled together, or "short-circuited," whereby the compressing side is then thrown into communication with the suction side, relieving the pressure entirely and establishing 125 an equilibrium. This relieving-passage may be placed in mid-position h in the cylinder A^2 , (see Fig. 6,) or may be divided and located at either extremity, which latter disposition I prefer in some cases. I would call attention, 130 first, that at the end of this stroke the greatest flow of gases takes place between the cylinders A^2 and A , necessitating the greatest opening of valve or valves C' . About this

time the mixture is exploded, and it sometimes happens that the "inflammation" permeates the gases of the interior of the cylinder A^2 and passage D and before the said valve C' can close, with the evident deleterious effects, the relieving-passages being such and so located as to release the pressure within cylinder A^2 and behind valve C' before the end of the stroke, and allowing it to seat itself properly before the ignition takes place. Secondly, the escaping gases to the suction side of the piston A^3 quickly raises the pressure and closes the induction-valve E' on the suction side, and at the same time releasing the closed valve E' on the compression side from the expanding gases, which fill the "clearance" spaces and passages and leaving it free to respond to the least suction as soon as the receding piston A^3 has covered the extremity of the releasing-passages $h' h'$. These may be of any convenient form; may consist of grooves, as shown, or holes may be bored and piped or connected to each other to accomplish the same result, as will readily be understood. It may be further pointed out that by the means of the releasing-passages $h' h'$ the only transfer of the gaseous mixture from the pump-cylinder to the combustion-cylinder is in the central portion of the "back-stroke," and is fully accomplished before any considerable degree of compression has taken place in the combustion-cylinder. The advantage is evident from the fact that the pressure in the pump-cylinder must be equal and even slightly in excess of the pressure of compression in the combustion-cylinder before the valves will open to admit the gases, and if the maximum transfer beat the last of the stroke it will also be at the time of maximum pressure, which pressure will then act upon the added areas of both pistons and consume a large percentage of the power given off by the explosion of the gases in the combustion-cylinder. It is to this evidently-bad arrangement that the low efficiency of the present single cycle-engines can be traced.

Having thus described the main features of the apparatus, by means of which the gaseous mixture is injected into the combustion-cylinder, I will next describe means of igniting same. The agent may be electricity, and may be produced by any suitable generator, as the battery I, Figs. 2 and 5. Any means for utilizing the current may be employed—as, for example, the spark from an induction-coil, high-tension generator, or a spark-coil I' may be included in the circuit, as shown in Figs. 2 and 5, which I prefer. To obtain a vigorous spark from a spark-coil, the circuit must be closed through the same for a certain period of time, then opened more or less suddenly. The spark occurs between the points where the circuit is opened. This spark-coil consists of a simple helix of wire wound upon an iron core, and is essentially different from a Ruhmkorff or secondary in-

duction-coil. In addition to this fact, it should be remembered that it is expedient to have the same generator and coil operate both ends or combustion-cylinders of the engine, and the following means are shown whereby this may be accomplished. The means, however, are equally adapted for operating the ordinary single-acting gas-engine.

In Figs. 1 and 2 the ignitor C is shown as being operated from a contact of the lever b' with cross-head a^2 when it is in its extreme positions. In Fig. 6, however, it is shown as being operated by the movement of the piston, the opposite ends of the engine being precisely identical with each other as to the internal arrangement of the combustion-cylinder, as will readily be seen. The arrangement of the igniting devices is such that, while the electrical current is closed through one ignitor, in the opposite end of the engine it remains in open circuit. One pole of the battery I is connected to the metallic parts of the engine by wire I^2 , the other to the insulated electrodes I^3 by wires i , as shown. Through the center of the insulation I^3 is a sleeve i' properly held within said insulation, which in turn is secured within the cylinder-head b^3 in any of the well-known methods. Within the sleeves i' are stems i^2 , Fig. 2, i^3 , Fig. 6, which are placed in electrical connection with wire i . Stems i^2 engage at their internal extremity a bell-crank lever J , fulcrumed at J' , and adapted to make and break contact at its free end with stationary electrodes J^2 , which are attached to the metal parts of the engine. The outer extremity of this stem i^2 is connected with lever J^3 , but insulated therefrom by thimble j . A rod j' connects the lower extremities of these levers and levers b' , adapted to engage the cross-head of the engine a^2 in the extreme portions of its oscillations.

Near the fulcrum j^2 of the lever J^3 there is a pointed lateral projection of this lever J^3 , which serves, in connection with the spring and roller attachment shown at j^3 , to form a combination suited to retain the levers in their extreme positions. The fulcrum j^2 is supported by the cylinder-head b^3 . The rod j' not only serves to connect the lever J^3 to the actuating-levers b' but also to the lever J^3 at the opposite end of the engine, as illustrated, which is given an identical movement. The movable electrode i^2 , however, protrudes from its opposite side into the cylinder, and the bell-crank lever J , at opposite ends of the engine, though given simultaneous movements will act oppositely, and when one is closing the other is in the act of opening the electrical circuit. Thus the igniting-spark resulting from the separating of that pair of electrodes which bear the relation of closed circuit alternates from one combustion-cylinder to the other, as is required, the changes of the circuit-connection being such that the one lever J completes the circuit and opens same before the other lever J completes the circuit, then this second lever J opens the

circuit before the first closes it again, and so on.

In Fig. 6 I show the preferred construction of ignitor, which contains the stem i^3 , and is made adjustable by a screw-thread. (Shown at its outer extremity.) The inner extremity is adapted to make and break the electrical circuit by the swinging of the lever K about the fulcrum K' , which is in connection with the metallic portions of the engine, and therefore represents the opposite pole of the generator I. An upward projection of the lever K engages with the pin K^2 , supported in sleeve K^3 and pressed inward by a strong spring L , thus holding the contact at the lower extremity of the lever K secure. A weight L' is also shown projecting laterally from fulcrum K' and serves the same purpose. The fulcrum K' of the lever K is supported by an independent block L^2 , properly secured, which is perforated near its lower extremity for the purpose of supporting the rod L^3 . This rod passes through the lever K , and is provided on either side of the same with buttons l and l' , which have convex faces turned toward the lever on its opposite sides. It is thought preferable that the aperture in the lever K , through which the rod L^3 protrudes, should be so large that the rod does not touch it nor drag upon it, but operates said lever solely by contact of the buttons l and l' upon its faces. The aperture will be noticed to be near the fulcrum K' , and there is preferably a slight amount of lost motion between the buttons and the lever. The rod L^3 passes the entire length of the three cylinders, and is provided with similar buttons l and l' and engages a similar lever K at the opposite end of the engine. The length of this rod, however, is such that while one lever K is in contact with its electrode i^3 the other is held away therefrom, as is shown in Fig. 6.

A tube l^2 is supported by the moving piston, through which passes the rod L^3 . One or more glands l^3 may be provided, the packing of which serves also the purpose of securing the necessary friction upon the rod L^3 .

A peculiar deflector, consisting of a tubular casting M , acting in conjunction with the extension M' of the passage leading to the air-pump A^2 , serves, by means of its upwardly-curved extremity, to lead the incoming fresh gaseous mixture to the point where the spark is about to be produced, thereby securing certainty of explosion. The particular shape shown is not necessary, as other shapes would doubtless suffice.

The exhaust-valve b is shown as operated from the crank-shaft in Fig. 1, and forms a contact with the moving cross-head in Fig. 6. These valves are of the usual construction, and when adapted to be operated by a device common to each other are so connected that one will be closed while the other is open, and vice versa. To the exact devices for operating (shown in connection with these valves) I do not care to limit my invention; but any

suitable means may be employed, whereby the proper operation is given to the valves on opposite ends of the engine.

Having thus described means by which my invention may be carried into practice, I will now proceed to state the operation of the several parts, which will be readily understood from the foregoing description. The cycle of the engine will be readily understood to be as follows: The piston being at one end of its stroke, the compressed mixture is ignited in one combustion-cylinder and the exhaust valve or opening is just being opened in the other combustion-chamber, and the pump piston or pistons, which move simultaneously in the two cylinders, or, what is the same in effect, the two ends of the same cylinder, operate as follows: The one has just injected its gaseous mixture into the combustion-cylinder taking the ignition; the other is filled with the mixture, ready to transfer the same into the now exhausting combustion-cylinder. The movement of the piston in one direction, during one-half the revolution of the crank-shaft, will transfer the mixture contained in one side of the pump-cylinder A^2 into the combustion-cylinder as the products of combustion are being exhausted, and in the other side of the pump-cylinder a fresh mixture of gas and air is being drawn for the next charge in the combustion-cylinder, which it serves. The operation of the valves E' and combining-valve G' will be readily understood from the drawings. These valves are of the usual construction and perform the usual function of the induction-valves of an ordinary pump. The action of the governing device upon the screws e will also readily be understood. The screw has a very steep pitch and requires only a few degrees of rotation to elevate the valve sufficiently from its seat to nullify to a large extent the transfer of gases into the combustion-cylinder. The operation of ignitors is extremely simple. The electrical generator I may be used separately or in connection with the spark-coil, as shown. The ignitors are in multiple-arc circuit, and are so mechanically coupled and actuated from the moving parts of the engine, either by the moving piston or the cross-head or other moving part, as is fully shown in Figs. 1, 2, and 6. The coupling, in all cases, however, should be such that each ignitor closes the circuit and then opens it upon it, upon which the first ignitor then closes the circuit. The entire force of the generator I is being spent upon one ignitor at a time. In Fig. 2 the contact with the cross-head a^2 changes the position of the actuating-levers upon each end of the cylinder, which vibrates the bell-crank levers J in the manner just described, one being open, while the other is in closed circuit relation. The opening or break of the circuit by these contacts interior to the cylinder produces a spark at the moment of the interception of the current, and thus ignites the gases. In Figs. 1 and 2 this interception

is just previous to the finishing of the compression-stroke, and if the engine is a very high-speed engine the full effect of the explosion or expansion of the gases after ignition will take place only after the pitman has passed the center and has started to advance in the other direction; but if the engine is employing a slower rate of speed the device shown in Fig. 6 is preferred, whereby the separation of the electrodes and ignition is produced after the crank-shaft has passed its center and is in the most favorable position for utilizing the immense strain produced by the explosion of the gases, for, as will be readily understood, the intense heat, and therefore the energy of the exploding gases, is almost instantly absorbed into the cold walls of the cylinder and thereby wasted, and if the position of the crank can be such as to fully and instantaneously utilize this energy a great saving will result. The causing of the electrodes to be separated by a dragging or frictional contact with the actuating element upon a moving part of the engine should be thoroughly understood, as it forms a novel feature in the matter of igniting of the mixture in a gas-engine. The deflector shown in Fig. 6 serves in bringing the fresh gases into the most favorable position for ignition at each time the spark is produced.

I do not care to limit myself to the exact construction of the parts herein shown, and in many equivalent arrangements could be provided for by carrying into effect the essential feature of my invention, which I have herein set forth.

I claim, and desire to secure by Letters Patent, the following:

1. In a gas-engine, a compound cylinder consisting of three cylinders, forming a single mechanical element, two combustion-cylinders separated by the fluid-pump cylinder, within which reciprocates a compound piston, in combination with passages connecting the cylinders, provided with valves opening into the end cylinders from the middle cylinder.

2. A gas-engine having two combustion-cylinders and a single fluid-pumping cylinder, in combination with a piston for these cylinders, consisting of a single mechanical element.

3. In a gas-engine, the pumping part thereof, in combination with two self-acting education-valves and induction-valves, the seating of which may be varied.

4. In a gas-engine, a cylinder provided with two jacketed ends and an enlarged central portion, in combination with a piston provided with three portions adapted to reciprocate, respectively, in the three portions of the cylinder.

5. In a gas-engine, two single-acting combustion-cylinders separated by a third cylinder of larger bore, and pistons for the three said cylinders, in combination with ducts or channels cast in the walls of the combustion-cylinder, and piston-rods attached to the

pump-piston, which are located in said ducts or channels.

6. In a gas-engine, the combination of two combustion-cylinders with a fluid-pump intermediately disposed, the latter adapted to be driven by said cylinders, a piston-rod, packing-box, or "gland" leading from said fluid-pump, and a power-shaft and connecting mechanism, substantially as shown and described, the arrangement being such that the combustion-cylinders deliver their power solely to the gas-pump, the power being transferred from the gas-pump piston to the power-shaft.

7. In a gas-engine, two opposite jacketed combustion-cylinders separated by a central cylinder of larger bore, the two jacketed cylinders being provided each with a plunger-piston bearing an annular enlargement located centrally upon said piston, which enlargement forms a piston for the centrally-located cylinder, the three cylinders being separate and distinct from each other.

8. In a gas-engine, two pistons for the combustion-cylinders, in combination with a piston for the pump-cylinder, and a valve or valves contained within ducts connecting the faces of like phase of the pistons which establish communication between the cylinders, and are contained within and move with said pistons.

9. In a gas-engine, a compound piston consisting of a cylinder with a concentric annular enlargement centrally located upon said cylinder, in combination with passages or ducts connecting the faces of the said enlargement with the nearest combustion-cylinders, and a valve or valves located in said passages.

10. In a gas-engine, two opposite jacketed cylinders separated by a central cylinder of larger bore, the two first being provided each with a plunger-piston, the two pistons connected by a central enlargement, forming a piston for the central cylinder, in combination with valves which are mounted in and move with said compound piston, opening toward the combustion-cylinders, and are connected, also, to the central cylinder, substantially as and for the purpose specified.

11. In a gas-engine, a compound piston consisting of a cylinder, with a concentric annular enlargement centrally located on such cylinder, in combination with passages or ducts connecting the faces of such enlargement with the combustion-cylinders, and a valve or valves located in said passages.

12. In a gas-engine, the combination of the valves C' C' and connecting-passages D and D', and cylinders A' and A, substantially as for the purpose specified.

13. In the fluid-pumping part of a gas-engine, the combination of a valve with an adjustable screw-stop, whereby the seating of the valve is regulated.

14. In the fluid-pumping part of a gas-engine, the combination of an adjustable screw-stop, with the induction-valve supporting same

- from its seat to a variable degree, and a governing device actuating said stop for the purpose of adjusting the travel of the valve.
15. In a fluid-pumping device for a gas-engine, the combination of the adjustable screw with an induction-valve and the governor F, substantially as and for the purpose specified.
16. In the double-acting pumping device of a gas-engine, two induction-valves communicating between the cylinders upon the opposite sides of the piston, and a passage between said valves, in combination with regulating devices for establishing more or less permanent communication between the ends of the pumping-cylinder.
17. In a gas-engine, the combination, with the induction-valves of the pump, of a third valve leading to a passage common to both induction-valves, and concentrically-located air and gas passages adapted to be covered by said third valve.
18. In a gas-engine, the combination of the valve E', valve G', air and gas passages G²G³, and concentric passages G G, substantially as and for the purpose specified.
19. In a gas-engine, the combination of a valve adapted to cover air and gas passages, an inclosure leaving a contracted passage between it and the valve, and a diffusing medium located immediately in front of said contracted passage, substantially as and for the purpose specified.
20. In a gas-engine, a valve governing the admission of the gas and air, of a recess in which said valve operates, and a collar upon said valve, which approaches the walls of said recess, and a diffusing medium near the recess so formed.
21. In a mixing device for gases in a gas-engine, the combination of a valve governing the flow of said gases, a narrow circular recess at the edges of the valve, and a perforated cap over said recess.
22. In a fluid-pump for a gas-engine, the combination of induction-valves, one at each end of the cylinder of said pump, with a common governing system for simultaneously preventing both valves from closing.
23. In a gas-engine, an ignitor operated by contact of a vibrating lever deriving its motion either from contact with the crank-shaft or cross-head of the engine, the electric contact being interior to the cylinder and sustained during one-half of the revolution of the crank-shaft of the engine.
24. In a gas-engine, and in combination with the ignitor thereof, a tubular projection or deflector secured within the cylinder and adapted to act in combination with a moving duct to receive the charge or a portion of the same coming from the fluid-pump.
25. In a gas-engine, a deflector adapted to lead the mixture to the ignitor, said deflector consisting of a stationary and a moving element.
26. In a gas-engine, a deflector consisting of the casting M and tube M', substantially as and for the purpose specified.
27. In a gas-engine, the combination, with the ignitor C, of deflector M and tube M', leading to the mixture-pump of the engine.
28. In the fluid-pumping device for a gas-engine, passages establishing communication between the spaces upon two sides of the piston of said pump during a portion only of its stroke uncovered by the piston.
29. In a gas-engine, the fluid-pumping portion thereof provided with passages opened by the movement of the piston of said pump for reducing the effective stroke-length of the piston.
30. In a gas-engine, the pumping device therein, the stroke of which is substantially the same as and simultaneous with that of the combustion-piston, in combination with relief-passages at or near the end of the stroke.
31. The pump-piston of a gas-engine secured to and moving with the combustion-piston, in combination with passages whereby the transfer of fluid into the combustion-cylinder is discontinued just before the end of the stroke.
32. In a gas-engine, the piston of the gas-pump secured to and moving with the piston of the combustion-cylinder, in combination with passages for cutting down pressure in the pump-cylinder in the latter part of the stroke.
33. A double-acting pumping portion of a gas-engine, in combination with passages for establishing communication between the spaces upon the opposite sides of the piston while the piston is near at the extreme portions of its stroke.
34. In a gas-engine, a piston which is common to both the combustion and pump cylinders, in combination with a valve opening toward the combustion-cylinder in a passage located between said two cylinders, and relief-passages designed to bring the said valve to its seat before the end of the stroke of the piston communicating between the cylinders and passages.
35. In a gas-engine, a pumping device, the capacities of which are in excess of that required, in combination with relief-passages, so arranged that the transfer of gases can only take place during the central portion of the stroke of said pump-piston.
36. In a gas-engine, a pump provided with the relief-passages h' h' at or near its ends, substantially as and for the purpose specified.
37. In a gas-engine, two ignitors actuated at the expiration of the stroke thereof from a common source oppositely connected to each other and consisting of moving levers internal to the cylinder.
38. In a gas-engine having more than one combustion-cylinder, and in combination with the ignition-contact interior to each combustion-cylinder, a common source of elec

- tricity, and multiple-arc circuit-connections from said source to said ignitors.
39. In a gas-engine, the combination, with two ignitors, of the generator I, spark or self-induction coil I', and electrical circuits, and moving contact-levers interior to the combustion-chamber, and consisting of moving levers internal to the cylinder, substantially as and for the purpose specified. 5
40. In a gas-engine, and in combination with a generator or source of electrical energy, two electrical ignitors interior to two combustion-cylinders coupled therewith in multiple-arc circuit. 10
41. In a gas-engine, a generator of electricity and circuits, in combination with two ignition-contacts interior to the two combustion-chambers, one of which only maintains the closed circuit relation at a time. 15
42. In a gas-engine, a generator of electricity and multiple-arc circuits, in combination with two ignition-contacts interior to two combustion-chambers, which make and break the electrical circuit alternately. 20
43. In a gas-engine, a generator of electricity and multiple-arc circuits, in combination with two igniting-contacts interior to two combustion-chambers, and actuating devices for causing one of said contacts to close the electrical circuit and break the same before the other closes said electrical circuit. 25
44. In a gas-engine, the combination of electrical generator-circuits, two ignition-contacts interiorly disposed to the cylinder, and actuating devices whereby the circuit of the generator is alternately completed through first one and then the other of the contacts. 30
45. In an igniting device for a gas-engine, levers interior to the combustion-cylinders forming a part of an electrical circuit, operating in conjunction with a contact interior to each of the combustion-cylinders also included in the electrical circuit, in combination with the moving part of the engine, and connecting devices for holding said lever from engagement with said contact during one-half of the revolution of the crank-shaft. 40
46. In an ignitor for a gas-engine, two levers connected and moving simultaneously interior to two combustion-cylinders by reason of contact with the moving part of the engine. 50
47. In a gas-engine, two separate cylinders, each provided with a vibrating lever, and a single rod connecting the levers, whereby the levers are vibrated simultaneously internal to each cylinder. 55
48. In a gas-engine, an ignitor-actuating part sustaining a sliding frictional contact with the moving parts. 60
49. In an ignitor for gas-engines, the vibrating lever, in combination with a rod which sustains a sliding frictional contact or engagement with a moving portion of said engine. 65
50. In an ignitor for a gas-engine, a vibrat-
- ing lever, in combination with a rod which sustains a sliding or rubbing frictional engagement with the moving portion of said engine and contact part or parts of the rod bearing such a relation to the lever as to provide a small open space or "lost motion" between the lever and rod. 70
51. In an ignitor for a gas-engine, a vibrating lever, in combination with a rod which contains a rubbing frictional engagement with a moving portion of the engine and passes near said lever for engagement with same, substantially as and for the purpose specified. 75
52. An ignitor for a gas-engine, consisting of two vibrating levers interior to two combustion-cylinders connected by a rod. 80
53. An ignitor for a gas-engine, consisting of two vibrating levers in separate compartments, in combination with a rod which extends from one compartment to the other. 85
54. A gas-engine having two cylinders connected by a common piston, in combination with a vibrating lever located within each cylinder and connected by a rod which sustains a frictional engagement with said piston. 90
55. In an ignitor for a gas-engine, two levers, in combination with a rod actuating the same, which rod passes near, but not in contact with, said levers, and is provided with stops adjacent to and upon the opposite side of said levers, substantially as and for the purpose specified. 95
56. In an ignitor for a gas-engine, the combination of a vibrating lever sustaining an electrical connection with the metallic parts of the engine, and an insulated electrode or contact adapted to connect with its free extremity, and a rod for actuating the same by rubbing or sliding frictional engagement with the moving part of said engine. 100
57. In an ignitor for a gas-engine, the combination, with two vibrating levers interior to two combustion-cylinders and connected to each other, of two insulated contacts and a common electrical generator, substantially as and for the purpose specified. 105
58. In combination with an ignitor for a gas-engine, a contact in each of two or more combustion-cylinders of the engine, a single-spark or self-induction coil, and a generator for the same, each contact adapted to close the circuit of the coil, one of such interior contacts only maintaining the closed-circuit relation at a time. 110
59. In an ignitor for a gas-engine, two simultaneously-vibrating contacts interior to separate cylinders, connected in like relation in connection with insulated electrodes or contacts, between which both levers are located, and a common generator or source of electricity. 115
60. In a gas-engine, the combination of levers k , rod L^3 , and moving part of the engine, substantially as and for the purpose specified. 120

61. In an electrical ignitor, the combination of levers K K, rod L³, and springs L L.

62. In an electrical ignitor, the combination of the lever K, rod L³, spring L, and contact 5 i³, substantially as and for the purpose specified.

63. In a gas-engine, in combination with the lever K and rod L³, casting L², adapted to support the lever and also the extremity of

10 the rod, substantially as and for the purpose specified.

64. In an ignitor for a gas-engine, the lever k, bearing the weight L'.

65. In a gas-engine, the combination of a piston rod or rods, a piston A³, cored duct or 15 passage within the walls of the cylinder, gland a³, and cylinder-head b³, substantially as and for the purpose specified.
